UNITED STATES PATENT OFFICE

156,658

TRICYCLE ACTION TOY

William J. Rahn, St. Albans, N. Y., assignor to
Paul Kohner and Frank Kohner, a copartner-
ship, doing business as Kohner Bros., New
York, N. Y.

Application May 20, 1948, Serial No. 146,484

Term of patent 7 years

(Cl. D34—15)

To all whom it may concern:

Be it known that I, William J. Rahn, a citizen
of the United States, residing at St. Albans, in
the Borough of Queens and State of New York,
have invented a new, original, and ornamental
Design for a Tricycle Action Toy, of which the
following is a specification, reference being had
to the accompanying drawing, forming part
thereof, in which

Fig. 1 is a side elevation of a tricycle action
toy, showing my new design,

Fig. 2 is a front elevation thereof, and

Fig. 3 is a plan view thereof.

I claim:

The ornamental design for a tricycle action toy,
as shown.

WILLIAM J. RAHN.
